Primary Examiner—Cathron C. Brooks
Assistant Examiner—Ricky Pham(74) Attorney, Agent, or Firm—Thorpe North & Western,
LLP(57) **CLAIM**The ornamental design for a toaster and steamer, as shown
and described.

DESCRIPTION

FIG. 1 is a front, right perspective view of the toaster and
steamer in accordance with our invention;

FIG. 2 is a front elevation view thereof;

FIG. 3 is a back elevation view thereof;

FIG. 4 is a right side elevation view thereof;

FIG. 5 is a left side elevation view thereof;

FIG. 6 is a top plan view thereof; and,

FIG. 7 is a bottom plan view thereof.

The broken lines shown in FIGS. 1-7 are for illustrative
purposes only and form no part of the claimed design
